SWITCH WITH MAGNETIC BLOW-OUTS

Application filed April 28, 1924, Serial No. 709,640, and in Germany May 14, 1923.

Switches for direct current or alternating current, wherein the switch arc is blown by a magnetic field, away from its point of origin and thereby drawn out, are frequently 5 constructed with the switch contacts located between two pole plates and thus are located in a uniform magnetic field. The lines of force of this magnetic field are approximately at right angles to the direction of the current in the generated switch arc, and the electric arc is thereby urged at right angles to its own length and at right angles to the direction of the lines of force, according to the well-known Fleming rule.

10 The effect of such arrangement is however greatly impaired or even annulled when the electric arc accidentally strikes at the edge of the contact surface instead of at the middle of the latter. In such a case it is found in practice that the arc, owing perhaps to the high magnetic permeability of the pole plates is urged, by its own magnetic field, beyond the edge of the contact surface and impinges against one of the pole plates 20 or against the insulating layer with which the pole plates are usually covered. Even with a single switching operation, and, in any case, frequent repetition of this operation, a metallic deposit is formed on this insulating layer at the pole plates. The electric arc then extends only from each of the contacts to this metallic deposit. The magnetic field between the pole plates is however incapable of exerting any effect upon these 25 remaining parts of the electric arc, because the current in these electric arcs flows in a direction parallel to the magnetic lines of force between the two pole plates. Consequently the electric arc, instead of being 30 constrained to move and so become extinguished, remains in its place and destroys or damages the switch.

Figure 1 is a diagrammatic drawing in plan of a magnetic blow-out device of known 45 construction;

Figure 2 is a diagrammatic drawing in plan of a magnetic blow-out constructed in accordance with the present invention;

Figure 3 is a diagrammatic elevation of a 50 pair of contacts and a blow-out device con-

structed in accordance with the invention and comprising a pair of energizing coils;

Figure 4 is a plan view of the arrangement shown in Figure 3;

Figures 5 and 7 are elevational diagrammatic views of further modifications or arrangements according to the invention;

Figure 6 is a plan view of still another modification.

In Figure 1 *a* are the contacts which are being drawn apart in the direction of the arrow *x*; *b* is the electric arc that is formed between them; *c* are the pole plates between which the magnetic field is indicated by the lines of force shown furnished with barbs. This magnetic field has the direction indicated by the barb on the axis *y* in Figure 1 and exerts upon the electric arc *b*, in which a current is flowing in the direction of the barb on the axis *x*, a force in the direction of the barb on the axis *z*, that is to say, perpendicular to the plane of the drawing. When, however, the electric arc strikes at the edge of the contacts (electric arc *b'*) and impinges upon the pole plates *c*, it consists substantially of two portions flowing in the direction of the arrow *y*, and one portion flowing in the direction of the arrow *x* which latter, in some cases, may no longer exist as an electric arc, but passes away as a line current in a metallic deposit.

Under such conditions the arc portions extending between the edges of the contact members *a* and the adjacent pole plate *c* are parallel to the lines of forces of the magnetic blow-out field. As a result, no force will be exerted between the field and the arc, leaving the latter stationary at the point where it started, with entire loss of the blow-out effect aimed at by the provision of the magnetic field.

The present invention has now for its object to provide an effective means for obviating that drawback of the usual arrangement, said means consisting in providing gaps in the pole plates over the place in which the switch arc is formed. The resulting arrangement is illustrated in Figure 2. In this figure, *a* are the contacts which are being drawn in the direction of the arrow *x*; *b'* is an electric arc which has struck on the edges of the

contacts and has thereby been deflected upwards. *a* are the pole plates which, in this case, are gapped at the place above the contact surfaces. The electric arc is now unable to impinge upon the pole plates, and therefore all the magnetic lines of force intersecting the electric arc remain effective. The magnetic force exerted upon the electric arc by the magnetic field is now not limited to that portion of the electric arc flowing in the direction indicated by the arrow *x*, but it also comprises chiefly the portions flowing in the direction indicated by the arrow *y*; these latter portions are hereinafter referred to as the 10 arc terminal or "foot" of the electric arc. The reason for this is that, in this improved arrangement, the magnetic lines of force do not have the same direction as the arrow *y*, but have, at the place referred to, also a component having the direction of the arrow *x*, so that these lines of force intersect the portions of the electric arc that flow in the direction indicated by the arrow *y*. It is this force, exerted upon the foot of the electric arc, which 20 produces the most effective movement of the electric arc.

In many cases it is desirable to employ only one exciting coil for the magnetic blow-out field. In such a case, according to this invention, integral pole plates slotted over the contact place may be employed for both switch contacts.

In other cases, where less importance is placed upon the employment of only one exciting coil, an additional and particular advantage can be gained, according to this invention, by providing separate pole plates for each switch contact, because in such cases it is not necessary to insulate the pole plates from the contacts. On the contrary, the pole plates may be connected directly to the contact pieces by screws or other means. In this manner the distance between the pole plates may be made as small as possible. The required number of ampere-turns, and therefore the dimensions of the exciting coil are diminished to such a degree that the two exciting coils required for two contacts are together generally not larger than the common 50 exciting coil in the case of integral pole plates.

The arrangement described with reference to Figure 2, has the advantage that, even if the electric arc strikes at the edges of the contacts, it will be driven further away by the magnetic field and extinguished. In some cases however it may remain permanently at the edges of the contacts, or at the edges of the arcing horns connected to these contacts, 60 so that, especially with pole plates mounted without insulation, there is the risk that the electric arc will overlap the pole plates and damage them. It is therefore desirable to move the electric arc, by means of the magnetic field, in such a manner that, even when

the said arc has struck on the edges of the contacts, it will, in its further movement along the arcing horns, be driven into the middle of the arcing path. This can be effected, according to the present invention, by making the arcing path include an angle with the contacts. 70

Figures 3 and 4 illustrate a constructional example of this arrangement in two projections, wherein, in agreement with the references used in connection with Figures 1 and 2,

Figure 3 is a view in the plane *x*—*z* taken along the direction of the axis *y*, and

Figure 4 is a view in the plane *x*—*y*, taken along the direction of the axis *z*.

In these figures, as before:—*a* are the contact pieces; *b* is the electric arc; *c* are the pole plates; *d* are the magnet cores; *e* are the exciting coils, one for each pair of pole plates, that is to say, for each contact; *f* are the arcing horns, the surface of which, shown in Figure 4, constitutes the arcing path. 80

The pole plates are screwed directly to the arcing horns without the interposition of an insulating layer at the places marked *g*. The arcing path includes, with the contact surface, on which the contacts *a* come in contact with one another, an angle which is assumed here to be a right angle. 90

The operation of this arrangement will be 95 clearly understood from inspection of the magnetic lines of force which are represented in Figure 4 by thin lines furnished with barbs. The magnetic lines of force are curved throughout the entire space wherein the arc may be started, or be moved on the contact members *a*, that is, on the portions of the contact members which are in engagement with each other when the circuit is closed, as well as on the side edges of said contact members and on the top thereof. The curved magnetic lines of force resulting from the foregoing arrangement of the pole plates with respect to the contact members, will, accordingly, always have a component in the direction of the axis *x*, or, in general, so directed as to cause the arc to be driven upward, and then along the arcing horns *f*, towards the center of the latter. So long as the electric arc is situated in the position shown in Figures 1 and 2, it will be acted upon, as above stated, only by forces having the direction of the axis *z*. 100

When, however, the electric arc is caused, by the blowing action of the magnetic field, to pass out of the space included between the contacts, and assume the position shown in Figure 3, the current in the foot of the electric arc will flow in the direction of the axis *z*. 110

The foot of the electric arc receives thus, 115 from the magnetic field component having the direction of the axis *x*, an urge in the direction of the arrow *y*, towards the middle of the arcing path. If the electric arc has struck at the edges of the contacts, it will therefore 120

follow the path indicated in Figure 4 by the long-dotted line i . This path is, at all points, at right angles to the projection of the magnetic lines of force shown in Figure 4, and it reaches the centre line of the arcing path quite near the point where the electric arc passes round the corner of the contact piece a from the contact surface on the arcing path. Experiments made with such switches have shown that this action occurs quite regularly, so that after repeated switchings, the arcing path surface situated between the two lines i in Figure 4 appears to be "sown" with traces of the electric arc, whereas no such traces are to be found outside the lines i .

The urge with which the electric arc, after passing the corner between the contact surface and the arcing path, is driven towards the middle of the arcing path, may be further increased, according to this invention, by setting the edges of the pole plates back from the arcing path, and bringing the said edges nearer to the arcing path in the direction 25 of the movement of the electric arc.

A constructional example of this arrangement is illustrated in Figure 5 wherein the reference letters have the same significance as in the preceding figures. The magnetic lines of force acting upon the arc terminal or foot of the electric arc extend, in this case, in planes which are situated at right angles to the edges of the pole plates, that is to say, which enclose an angle α with the $y-z$ plane. 30 α is also the angle between the edges of the pole plates and the arcing path. The magnetic lines of force, therefore, here also have a component in the direction of the axis x , namely along the entire stretch along which 35 the edges of the pole plates enclose the angle α with the arcing path; in some cases, therefore along the entire arcing path. The force which has a tendency to drive the electric arc to the middle of the arcing path is therefore, 40 in this case, not limited only to the corner between the contact surface and the arcing path, and their immediate proximity, but occurs also in the further advance of the electric arc, although to a less extent.

45 A further means for achieving the same end consists, according to this invention, in that instead of arranging the pole plates parallel to each other, they are arranged to converge together in the direction of the movement of the electric arc in the manner illustrated by way of example in Figure 6. This arrangement has the effect of causing the magnetic lines of force to have components in the direction of the arrow x at the places 50 above referred to.

In both arrangements shown in Figure 5 and Figure 6 it is not necessary that the inclined position of the pole plates or of their edges relatively to the arcing path shall extend over the whole length of the arcing

path. This inclined position may be provided only here and there, and in some cases may be repeated in several places. An example of such an arrangement is illustrated in Figure 7 in which the edge of the pole plates has a serrated formation.

In the switches or circuit breaker devices described hereinabove, I have thus combined a number of features which greatly improve the blow-out action exercised by the magnetic field on the interrupting arc incident to the opening of a circuit. By setting back the edges of the pole plates behind the ends of the contact surfaces of the arcing contacting members a the magnetic field in the vicinity of the arc terminals is given a shape as to positively secure arc movement in the direction towards which it is to be blown independently of the point where the arc has been started, whether in the middle of the contact members, or towards the edges thereof. The provision of a magnetic blow-out mechanism in which a distinct set of pole plates is associated with each of the contact members, and so arranged that the two sets of pole plates are substantially in contact with the associated contact members, but the two sets are insulated from each other, with a gap between the two sets of pole plates at the points where the arc is started, secures not only the above mentioned improved blow-out action, but also solves the many difficulties incident to the proper insulation of the contact members with respect to the pole plates, so as to secure satisfactory opening of the circuit and avoid bridging of the contact members by a deposit of conducting particles on the walls of the closed arc chutes in the prior art constructions.

The shaping of the contact surface of the arcing members and of the adjacent surface of the arcing horn, by bending the path of arc travel, secures, in conjunction with the offset magnetic pole plates, definite upward movement of the arc terminal from the point where the arc was started, and in the course of the further travel thereof, its movement towards the center of the arc travel surface on the arcing horns; the inclination of the edges of the pole plates to the surface of the arcing horns and the greater spacing between the pole plates near the starting point of the arc than at the further removed points of the arc horns, still further increases the directional control of the arc movement over the entire path of its travel.

Switches constructed according to the present invention are distinguished above all by their very compact design. They are suitable for use as elements for controllers and similar apparatuses comprising a plurality of switch elements, and especially for use with high voltage current on account of the possibility of dispensing with the insulation of the pole plates.

While only the switch contacts α and the various parts or elements immediately associated therewith have been shown and described, it will be understood that the various other parts of the circuit breaker, such as the supporting members for the contacts and the mechanism for effecting movement of the same into and out of contacting relation, may be of any suitable construction, such as is found in the usual circuit breakers of this general type.

What I claim is:—

1. In a circuit breaker device, a pair of separable arcing-contact members, an arcing horn extension member associated with each of said contact members, and a magnetic blow-out device for causing the arc drawn between said contact members to travel into the space between said horn extension members and comprising a pair of pole-shoe plates disposed adjacent to one of said contact members, said pole plates having edges set back of the edges of the contact surface of said contact member and converging towards the edge of the surface of travel of said arc on the associated horn extension member, and means for inducing a magnetic flux taking a curved path from the edge of the pole-shoe plate on one side of a contact member, over the surface of travel of the arc terminal on said contact member and the arc-horn extension, toward the corresponding edge of the pole-shoe plate disposed on the other side of said contact member.
2. The combination with a circuit breaker having a pair of separable arcing contact members and an arc-travel path towards which the arc drawn between said contact members is blown, of a magnetic blow-out device operable to cause the arc to travel along said path and comprising a pair of pole-shoe plates having pole surfaces converging in the direction of the arc travel along said path.
3. The combination with a circuit breaker comprising a pair of separable arcing contact members and horn extensions associated with each of said contact members, of a magnetic device for blowing the arc between said contact members into the space between said horn extension members, said device comprising a pair of pole-shoe members extending on both sides of one of said contact members and the associated horn extension, said pole-shoe members having magnetic pole surfaces set back of the edges of the surface of travel of the arc terminal on said contact members and said horn extensions, said pole surfaces converging towards each other in the direction of the arc travel.
4. The combination with a circuit breaker comprising a pair of separable arcing contact members and horn extensions associated respectively with said contact members, of a magnetic device for blowing the arc between said contact members into the space between

said horn extensions, said device comprising a pair of pole-shoe members extending on both sides of one of said contact members and the associated horn extension, said pole-shoe members having magnetic pole surfaces set back of the edges of the surface of travel of the arc terminal on said contact member and said horn extension, said pole surfaces converging towards each other in the direction of the arc travel, the path of arc travel on said horn extension being inclined to the contact surface between said contact members.

5. In electric switch apparatus, laterally-spaced elements disposed to provide a path for magnetic flux, a switch contact disposed intermediate said elements and electrically connected thereto, said elements converging towards each other from their respective end portions adjacent said contact toward their other end portions.

6. In an electric switch with magnetic blow-out apparatus comprising switch contacts located between pole plates, the plates being gapped in the region of the initial arc and arranged to form an angle with the plane of movement of the arc and approaching the plane in the direction of the movement of the arc root.

7. In an electric switch with magnetic blow-out apparatus comprising switch contacts, pole plates arranged along the sides of said contacts, said pole plates being gapped in the region of the initial arc formed during a switching operation, and arcing horns along which the arc travels, said pole plates being arranged to approach said horns in the direction of travel of the arc and defining an arcing path therewith, said horns being so located relative to the arcing path as to include angles formed by said pole plates with said switch contacts.

In testimony whereof I have signed my name to this specification.

OSKAR ZINGG.
